UNITED STATES PATENT OFFICE.

JACKSON L. KAIL, OF CHICAGO, ILLINOIS, ASSIGNOR TO THE WINSLOW BROS. COMPANY, OF CHICAGO, ILLINOIS, A CORPORATION OF ILLINOIS.

DOOR-HANGER.

1,069,261.

Specification of Letters Patent.

Patented Aug. 5, 1913.

Application filed May 6, 1912. Serial No. 695,438.

To all whom it may concern:

Be it known that I, JACKSON L. KAIL, a citizen of the United States, residing at Chicago, in the county of Cook and State of Illinois, have invented new and useful Improvements in Door-Hangers, of which the following is a specification.

This invention relates to door hangers, and the object of the invention is to produce an easy running and practically noiseless door hanger of improved and novel construction.

The invention consists in the several novel features hereinafter set forth and claimed.

15 The invention is clearly illustrated in the drawing furnished herewith, in which:—
Figure 1 is a side elevation, (looking from the well side of an elevator inclosure) of an elevator door and track, partly broken away, and showing a pair of hangers, embodying one form of the present invention, supporting the door from the track, Fig. 2 is a detail side elevation, partly broken out, of one of the hangers and fragments of the track and door, the view being in the direction opposite to that seen in Fig. 1, and one of the track elements removed, Fig. 3 is a vertical cross section taken on the broken line 3—3 of Fig. 2, Fig. 4 is a view partly in plan and partly in horizontal section of the hanger, certain parts being broken away and certain parts detached from others.

Referring to the drawings, A is a fragment of an elevator door of ordinary construction, B a track which is secured to the elevator inclosure in the usual manner well known to those skilled in the art, and C is a pair of door hangers embodying the present invention, secured to the top of the door and traveling upon the tread of the track B. In the form illustrated in the drawing, said track comprises a vertical web b, having a horizontally extending flange b¹, at its top which overhangs the hangers to prevent them from being lifted far enough for accidental displacement from the track, and b², represents the main rail of the track which, as shown, is formed in its upper face with a longitudinal groove b³, preferably of 50 curved or arc shaped cross section.

The hanger C, has as a part thereof, a bracket c, secured to the door A, and said bracket is connected with a block C¹, around which are grouped a number of anti-friction elements such as balls c¹. The balls c¹ are

spaced apart and connected together by an endless chain C², here shown as comprising links c², pivotally connected together by rivets c³. Each link preferably comprises two symmetrical halves, each formed with a concave portion c⁴, between which is rotatively secured one of the balls c¹, with the ball projecting considerably above and below the upper and lower edges of the link. The block C¹, is of elongated formation and has a continuous track around the same, comprising upper and lower horizontal trackways c⁵, connected to each other at their ends. Preferably said horizontal trackways are in the form of grooves in the upper and lower edges of the block C¹. The ends c⁶, of the block are rounded off to present curved or arc shaped surfaces which merge into the horizontal trackways by way of oblique trackways c⁷. It is to be observed that an odd number of balls and links are employed; this makes it possible to avoid any considerable slack in the chain C², and in fact with parts having the proportions illustrated in Fig. 2, the chain and ball device may fit tight on the trackway around the block C¹. It is to be observed that when a door (supported by a pair of my present hangers) is moved in either direction, the balls roll upon the tread b³, of the supporting track and around the block C¹, on the trackways c⁵, c⁶, c⁷, the weight of the door being transmitted from the hangers to the supporting track by those balls traveling between the block C¹, and track B.

The construction of hanger above described, provides one which is extremely easy running, noiseless and capable of slidably supporting comparatively heavy doors or other objects. By lengthening out the block C¹, the number of balls, upon which said block rests, may be increased as is desired, and although balls have been chosen for the purpose of illustrating the invention, it is perfectly obvious that other forms of anti-friction rolling elements may be substituted for the balls shown. While the hanger has been shown as described in connection with an elevator door, it is perfectly obvious that its use is not limited thereto, as there are many other places where a hanger of this kind may be employed.

I realize that various alterations and modifications of this device are possible without departing from the spirit of my

invention, and I do not therefore desire to limit myself to the exact form of construction shown and described.

I claim as new and desire to secure by 5 Letters Patent:

In a door hanger, the combination with a track, of a horizontally elongated block, above and in the plane of the track, having parallel upper and lower edges provided 10 with ball races and merging into rounded end faces of the block, a series of spaced uniform balls in constant contact with the

edges of the block and connected by a vertically flexible chain holding each ball at its equatorial zone only, and means for suspending a door from the block. 15

In witness whereof, I have hereunto signed my name at Chicago, Cook county, Illinois, this 30th day of April 1912.

JACKSON L. KAIL.
